UNITED STATES PATENT OFFICE.

ERNEST ASHTON, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

FINISHING WHEEL.

Application filed March 3, 1924. Serial No. 696,513.

This invention relates to finishing wheels and is illustratively shown as embodied in a buffing wheel designed for scouring the breasts of Louis heels.

5 The requirements of this type of work necessitates wheels of considerable size, sometimes as much as eleven inches in diameter, which may be run at very substantial speeds. The resulting centrifugal force 10 has made the types of wheel now in use, some of which are constructed of wood and others of cast metal, unsatisfactory and dangerous. Trouble has been experienced with the wooden wheels because of the insufficient 15 strength of the material itself. Moreover, such wheels have usually been made of sections pivotally connected to provide for replacement of the abrasive coverings and in the case of cast metal wheels, the inherent 20 weight of the parts has rendered the locking devices for the two sections unsafe.

Accordingly, an object of the present invention is to provide an inexpensive construction which will be light and at the same 25 time have very considerable strength.

In the attainment of this object, the present invention provides an improved finishing wheel comprising, as herein illustrated, a sheet metal body member having its flange 30 transversely slotted to receive the ends of an abrasive scouring or buffing strip which encircles the flange, the inner side of the flange being provided on one side of the slot with means to secure one end of the abrasive 35 strip, and having a strip-tightening and securing member secured at the other side of the slot and carrying means to secure the other end of the abrasive strip. The invention also provides a locking member, illustrated as a spring-strip detachably secured at its ends to the inner side of the flange, on the opposite sides of the slot, having projections constructed and arranged to lock the 40 ends of the abrasive strip against the inner side of the flange on the opposite sides of the slot by pressing against the tightening and securing member. In this construction, lightness has been obtained without sacrifice 45 of inherent strength, and at the same time, the illustrated wheel has adequate provision 50 for detachably securing and locking the abrasive covering to the wheel in such man-

ner as to provide for convenient detachment and replacement.

In the accompanying drawings forming a 55 part of this specification,

Fig. 1 is a side elevation of a buffing wheel to which an abrasive strip has been applied;

Fig. 2 is a front elevation with the padding shown in section; and

Fig. 3 is an enlarged side elevation illustrating the method of applying the abrasive strip.

At the center of the cup-shaped member 65 10, which is stamped from sheet metal to the cross-section shown in Fig. 2, there is secured by screws 14 a hub 18 having a flange 12. This hub has a portion 20 projecting through the metal cup for additional 70 strength and is provided with set screws 16 to hold the wheel on a shaft. The cup-shaped member 10 has a peripheral flange 22 to which there is riveted a leather surface strip 24 and surrounding this leather strip 75 is a cushion member 26 which may be formed of felt or any other suitable resilient material. This felt rim 26 has its external surface shaped in the desired cross-section and forms a backing for the abrasive strip 80 30 which entirely surrounds the wheel. It will be noted that the peripheral flange 22 of the wheel is slotted at 32 to allow the insertion of the ends of the abrasive strip. At 85 one side of this slot 32 and projecting inwardly from the flange 22 are two pointed pins 34. One end of the abrasive strip is forced over these pins, while the other end is then carried through the slot 32 and around the wheel and again brought through 90 the slot 32 to be fastened. In order to tighten the abrasive strip and secure it in position, a hinged securing and tightening lever 36 is pivoted to the inside of the flange 22 on the side of the slot 32 opposite from the 95 pins 34. This lever has an end portion 38 which is designed to lie closely against the inner flange 22 when the lever is swung adjacent thereto, as shown in Fig. 1. On the flat portion 38, there is provided a sharp- 100 ened pin 40 facing away from the slot. The end portion of the abrasive strip 30 is brought around and over the pin portion 38 of the lever 36 and forced over the pin 40

when the lever is in its raised position, as shown in Fig. 3. The lever may then be depressed manually to tighten the strip 30 until the portion 38 brings the end of the 5 abrasive strip against the flange 32, an aperture 42 being provided for the admission of the pin 40. This tightening lever is then held in the latter position by means of a spring member 50 adapted to engage beneath 10 hook members 54 secured to the inner periphery of flange 22. The hook members 54 are preferably formed by stamping in a portion of the peripheral flange 22 of the sheet metal member 10. This is best shown 15 in Fig. 2. It will also be noted from this figure that the spring member 50, which is shown in dotted lines therein, is of substantial width and has its ends slotted at 52 to form projecting tabs 53 which are curved inwardly and 20 engage the opposite sides of the hook members 54 the better to retain the spring member in position. The spring member 50 is provided, intermediate its ends, with two humps 56 and 58 which are arranged to engage 25 the ends of the abrasive strip. The hump 56 bears against the strip immediately adjacent to the flattened portion 38 and holds the strip and the lever against the flange 22. The other hump 58 presses the 30 other end of the abrasive strip against the flange 22 at a point between pins 34. The manner of use of the buffing wheel will be apparent to those skilled in the art, it being obvious that it is intended to be mounted 35 upon a power-driven shaft and the work applied to the abrasive strip which surrounds the periphery of a wheel.

Having thus described the invention, what I claim as new and desire to secure by Letters Patent of the United States is:—

40 1. A finishing wheel having a peripheral flange provided with a slot extending transversely through it, pins projecting from the inside of the flange at one side of the slot to engage and secure one end of an abrasive strip which is passed around the wheel and has its other end inserted through the slot, and a securing member for said other end of the strip mounted on the inside of the flange 45 at the other side of the slot and having a strip-engaging pin facing away from the slot.

50 2. A finishing wheel having a peripheral flange provided with a transverse slot, means mounted inside the periphery of the wheel adjacent to one side of said slot for securing one end of an abrasive strip which is passed around the wheel and has its other end inserted through the slot, and a lever pivoted 55 upon said flange upon its inner side adjacent to the other side of said slot and provided

with a securing member for said other end of the strip which member faces away from the slot.

55 3. A finishing wheel having a peripheral flange provided with a transverse slot, means carried by the inner side of the flange for engaging the ends of an abrasive strip adjacent to either side of said slot, and a spring strip constructed and arranged to be 60 detachably secured at its ends to the inner side of the flange and to press against the ends of the abrasive strip to lock them detachably to said inner side on either side of said slot.

65 4. A buffing wheel comprising a sheet metal member having a peripheral flange provided with a slot, an abrasive strip encircling said flange and having its end portions threaded through the slot, and means for 70 securing one end of the abrasive strip to the inner side of the flange alongside the slot, a strip-tightening and securing member provided with strip-engaging members on its surface away from the slot, and means for 75 pressing said tightening and securing member and the abrasive strip against the inner side of the flange.

80 5. A buffing wheel having a peripheral flange provided with a slot extending 90 through it transversely, an abrasive strip encircling said flange and having its end portions inserted through the slot, and means for securing said ends of the strip to the inner side of the flange comprising a resilient member detachably secured at its 95 ends to the inner side of the flange and provided with projections constructed and arranged to lock the ends of the abrasive strip against the inner side of the flange on the 100 opposite sides of said slot.

105 6. A buffing wheel having a peripheral flange member provided with a slot extending through it transversely, an abrasive strip surrounding said flange and having its ends inserted through said slot, means for securing one end of said strip at one side of the slot, means for securing the other end of the strip at the other side of the slot comprising a hinged member having its end portion 110 constructed and arranged to move away from the slot and approach the inner side of the flange, and means arranged on the inside of the wheel constructed and arranged to bear against the end of the abrasive strip which has been secured to said hinged member to press that end of the strip against the inner side of said flange.

115 In testimony whereof I have signed my name to this specification.

ERNEST ASHTON.
